UNITED STATES PATENT OFFICE.

JOHN M. FEDDERS, OF BUFFALO, NEW YORK, ASSIGNOR TO FEDDERS MANUFACTURING COMPANY INC., OF BUFFALO, NEW YORK, A CORPORATION OF NEW YORK.

RADIATOR CORE.

Application filed January 25, 1928. Serial No. 249,244.

This invention relates to a core which is more particularly intended for use as part of a radiator for cooling the water of gas engines although the same may also be used 5 for other purposes.

One of the objects of this invention is to produce a radiator core in which a minimum amount of double metal is used and instead a maximum amount of single thickness of 10 metal is exposed to the atmosphere and thereby increase the radiating efficiency for a given amount of metal.

Another object of this invention is to increase the strength of the core and thereby enable the radiator to resist injury when used for heavy work.

A further object of this invention is to provide a radiator core having few parts which are of simple construction, which are capable 20 of being manufactured readily and which can be quickly, easily and accurately assembled into their proper relative position without requiring specially skilled help or elaborate apparatus for this purpose.

25 In the accompanying drawings:—

Figure 1 is a fragmentary front elevation of a radiator embodying my invention.

Figure 2 is a top plan view of the same.

Figures 3 and 4 are horizontal sections 30 taken on the correspondingly numbered lines in Fig. 1.

Figures 5 and 6 are vertical transverse sections taken on lines 5—5 and 6—6 respectively in Fig. 2.

35 Figures 7 and 8 are vertical longitudinal sections taken on the correspondingly numbered lines in Fig. 1.

Figures 9 and 10 are perspective views of 40 one of the water tube walls and one of the radiating fins.

In the following description, similar characters of reference indicate like parts in the several figures of the drawings.

45 The numeral 20 represents the plurality of vertical water tubes of the radiator core and 21, the plurality of horizontal air passages arranged between the water tubes.

Each of the water tubes consists of two upright wall strips 22 of sheet metal which are 50 arranged side by side each strip having its opposite longitudinal edges bent inwardly to form offsets 23, which engage with the corresponding offsets of the companion wall strip as shown in Fig. 3, and are connected there- 55 with by soldering or otherwise so as to form

a water tube which is closed at its edges. These offset edges of the water tube walls are preferably bent into zig-zag or corrugated form, as shown at 24 in Figs. 1 and 9, so as to strengthen the radiator, also to increase 60 the radiating surface of the core for a given height and also to give the same a cellular appearance when assembled with the radiating fins or spacers of the core.

Between its longitudinal edges each water 65 tube wall strip is provided with a plurality of upright stiffening beads 25 which are bent so as to project inwardly and engage the corresponding stiffening beads 25 of the companion wall strip of the respective water tube, 70 as shown in Figures 2, 3, 4, and 5, thereby bracing these walls relatively to each other and materially strengthening the tube and enabling the same to effectively resist the strains to which the same is subjected.

Each of the water tube wall strips is also provided between its longitudinal edges with a plurality of horizontal seat beads 26 which are bent so as to project inwardly, the base or bottom on the concave side of these beads being preferably in line and flush with the outer summits of two corresponding corrugations on the longitudinal edges of the respective wall strip, as shown in Figures 1, 4, and 9. These seat beads on each wall strip are of less 80 depth than the stiffening beads and spaced apart from the corresponding seat beads of the companion wall strip, as shown in Figs. 3 and 9, for a purpose which will presently appear.

90 The air passages are preferably formed between the several water tubes by a plurality of radiating fins or spacers, each of which consists of a strip 27 of sheet metal which is bent to form a succession of two sets of loops 95 270 projecting alternating in opposite directions. The summit of each loop is preferably pinched closely together to form a narrow double thickness edge portion 27 which engages with the summits of two corresponding 100 corrugations on the longitudinal edges of the respective wall strip and also with the bases or bottoms of the seat beads of the respective wall strip, the several edges 27 of the summits on the fin loops, and the surfaces of the respective wall strip with which they engage being connected by soldering in any suitable or approved manner so that the several tube wall strips and fin strips are practically one 105 integral structure which is very strong and 110

durable and not liable to give way under heavy duty.

The edge portions 27 of the fin loops do not interlock with these grooves or channels formed on the wall strips by the longitudinal beads 25 but instead bridge the same, as shown in Figs. 4 and 5, whereby the metal of these edges is exposed to the air at these places as shown at 40 and a correspondingly greater radiation of heat to the atmosphere than otherwise would occur if these surfaces engaged each other and interposed a double thickness of metal through which the heat would have to pass.

Each loop of the radiating fin has the central part 28 of its plies or sides bent toward each other so that the loop has substantially the form of a keyhole, and this bending is preferably of angular form, as shown in Figures 1, 5, and 6, so that the radiator core presents a cellular appearance. The sides or plies of the loops do not engage each other, thereby fully exposing the plies of each loop on its opposite sides and thereby obtaining the maximum radiating effect.

For the purpose of further increasing the radiation of heat by the fins to the atmosphere each side or ply of a loop is provided with a plurality of crosswise slits 29 and the metal between each pair of slits is deflected so as to form a baffle web 30 which extends across the concave sides of the respective loop side, as shown in Figs. 1, 5, and 6, and therefore presents an obstruction to the air moving through the air passages and causes the latter to take up more of the heat from the water which is to be cooled.

To permit the webs to thus extend across the air path and still permit of bending the plies of the loop into keyhole form each web is shortened by crimping the same, this being accomplished by reversely bending a part of the web as shown at 31 and deflecting a part thereof, as shown at 32.

As a whole this core has greater strength and radiating capacity for a given amount of metal used and can also be produced expeditiously and at comparatively low cost.

I claim as my invention:

1. A radiator core containing a plurality of water tubes and a plurality of air passages arranged between said water tubes, each of said water tubes consisting of two wall strips of sheet metal each of which has its opposite longitudinal edges offset inwardly and engaging with the corresponding inwardly offset longitudinal edges of the companion wall strip, and each wall strip being provided intermediate of its longitudinal offset edges with a plurality of longitudinal inwardly deflected stiffening beads and a plurality of transverse inwardly deflected seat beads, intersecting said longitudinal beads at right angles, and said air passages being formed by sheet metal radiating fins arranged be-

tween adjacent water tubes and engaging with the bases of the seat beads on the walls thereof.

2. A radiator core containing a plurality of water tubes and a plurality of air passages arranged between said water tubes, each of said water tubes consisting of two wall strips of sheet metal each of which has its opposite longitudinal edges offset inwardly and engaging with the corresponding inwardly offset longitudinal edges of the companion wall strip, and each wall strip being provided intermediate of its longitudinal offset edges with a plurality of longitudinal inwardly deflected stiffening beads and a plurality of transverse inwardly deflected seat beads intersecting said longitudinal beads at right angles, and said air passages being formed by a sheet metal strip which is bent to form a succession of two sets of loops projecting alternately in opposite directions and the summits of each set of loops engaging with the bases of the transverse beads on the exterior of one of the walls of each water tube.

3. A radiator core containing a plurality of water tubes and a plurality of air passages arranged between said water tubes, each of said water tubes consisting of two wall strips of sheet metal each of which has its opposite longitudinal edges offset inwardly and engaging with the corresponding inwardly offset longitudinal edges of the companion wall strip, and each wall strip being provided intermediate of its longitudinal offset edges with a plurality of longitudinal inwardly deflected stiffening beads and a plurality of transverse inwardly deflected seat beads intersecting said longitudinal beads at right angles, and said air passages being formed by a sheet metal strip which is bent to form a succession of two sets of loops projecting alternately in opposite directions and the summits of each set of loops engaging with the bases of the transverse beads on the exterior of one of the walls of each water tube, each of said loops having the central parts of its sides bent toward each other so that the loop is of substantially keyhole form.

4. A radiator core containing a plurality of water tubes and a plurality of air passages arranged between said water tubes each of said water tubes consisting of two wall strips of sheet metal each of which has its opposite longitudinal edges offset inwardly and engaging with the corresponding inwardly offset longitudinal edges of the companion wall strip, and each wall strip being provided intermediate of its longitudinal offset edges with a plurality of longitudinal inwardly deflected stiffening beads and a plurality of transverse inwardly deflected seat beads intersecting said longitudinal beads at right angles, and said air passages being formed by a sheet metal strip which is bent to form a succession of two sets of loops projecting al-

- ternately in opposite directions and the summits of each set of loops engaging with the bases of the transverse beads on the exterior of one of the walls of each water tube, and 5 each of said loops having its summit pinched closely together to form a rib which forms a narrow edge for engaging the respective seat on the opposing water tube wall.
5. A radiator core containing a plurality 10 of water tubes and a plurality of air passages arranged between said water tubes, each of said water tubes consisting of two wall strips of sheet metal each of which has its opposite longitudinal edges offset inwardly and en- 15 gaging with the corresponding inwardly offset longitudinal edges of the companion wall strip, and each wall strip being provided intermediate of its longitudinal offset edges with a plurality of longitudinal inwardly de- 20 flected stiffening beads and a plurality of transverse inwardly deflected seat beads intersecting said longitudinal beads at right angles, and said air passages being formed by 25 a sheet metal strip which is bent to form a succession of two sets of loops projecting alternately in opposite directions and the summits of each set of loops engaging with these bases of the transverse beads on the exterior 30 of one of the walls of each water tube, each of said loops having the central parts of its sides bent toward each other so that the loop is substantially of keyhole form, and each side being slotted crosswise and the metal between 35 each pair of slits deflected to form a radiating web which is arranged across the concave faces of each side, and each web being crimped for adapting the length of the same to the length of the respective side. 40
6. A radiator core containing a plurality 45 of water tubes and a plurality of air passages arranged between said water tubes, each of said water tubes consisting of two wall strips of sheet metal each of which has its opposite longitudinal edges offset inwardly and en- 50 gaging with the corresponding inwardly offset longitudinal edges of the companion wall strip, and each wall strip being provided intermediate of its longitudinal offset edges with a plurality of longitudinal inwardly de- 55 flected stiffening beads and a plurality of transverse inwardly deflected seat beads intersecting said longitudinal beads at right angles, and said air passages being formed by 60 a sheet metal strip which is bent to form a succession of two sets of loops projecting alternately in opposite directions and the summits of each set of loops engaging with the bases of the transverse beads on the exterior 65 of one of the walls of each water tube, and the offset edges of said wall strips being corrugated and the summits of said corrugations facing the summits of said loops. 70
7. A radiator core containing a plurality 75 of water tubes and a plurality of air passages arranged between said water tubes, each of said water tubes consisting of two wall strips of sheet metal each of which has its opposite longitudinal edges offset inwardly and en- 80 gaging with the corresponding inwardly offset longitudinal edges of the companion wall strip, and each wall strip being provided intermediate of its longitudinal offset edges with a plurality of longitudinal inwardly de- 85 flected stiffening beads and a plurality of transverse inwardly deflected seat beads intersecting said longitudinal beads at right angles, and said air passages being formed by 90 a sheet metal strip which is bent to form a succession of two sets of loops projecting alternately in opposite directions and the summits of each set of loops engaging with these bases of the transverse beads on the exterior 95 of one of the walls of each water tube, each of said loops having the central parts of its sides bent toward each other so that the loop is substantially of keyhole form, and each side being slotted crosswise and the metal between 100 each pair of slits deflected to form a radiating web which is arranged across the concave faces of each side, and each web being crimped for adapting the length of the same to the length of the respective side. 105
8. A radiator core containing a plurality 110 of water tubes and a plurality of air passages arranged between said water tubes, each of said water tubes consisting of two wall strips of sheet metal each of which has its opposite longitudinal edges offset inwardly and en- 115 gaging with the corresponding inwardly offset longitudinal edges of the companion wall strip, and each wall strip being provided intermediate of its longitudinal offset edges with a plurality of longitudinal inwardly de- 120 flected stiffening beads and a plurality of transverse inwardly deflected seat beads intersecting said longitudinal beads at right angles, and said air passages being formed by 125 a sheet metal strip which is bent to form a suc-

cession of two sets of loops projecting alternately in opposite directions and the summits of each set of loops engaging with the bases of the transverse beads on the exterior of one of the walls of each water tube, and the offset edges of said wall strips being bent into zig-zag form and the summits of said offset edges

being in line with the bases of the corresponding bases of the seat beads on the respective wall strip and engaging with the opposing 10 summits of said radiating loops.

In testimony whereof I affix my signature.

JOHN M. FEDDERS.
